US00D872709S

(12) **United States Design Patent** (10) Patent No.: **US D872,709 S**
(45) Date of Patent: **** Jan. 14, 2020**

(54) **AUDIO BLUETOOTH CONVERTER**

(71) Applicant: **Shenzhen Riitek Technology Co., Ltd.**,
Shenzhen, Guangdong (CN)

(72) Inventors: **Xianyong Pang**, Guangdong (CN);
Junkui Chen, Guangdong (CN)

(73) Assignee: **Shenzhen Riitek Technology Co., Ltd.**,
Shenzhen (CN)

(**) Term: **15 Years**

(21) Appl. No.: **29/653,283**

(22) Filed: **Jun. 13, 2018**

(51) LOC (12) Cl. **14-03**

(52) U.S. Cl.
USPC **D14/217**

(57) **CLAIM**

The ornamental design for a audio bluetooth converter, as shown and described.

DESCRIPTION

FIG. 1 is a top view of an audio bluetooth converter showing my new design.

FIG. 2 is a bottom view thereof.

FIG. 3 is a front view thereof.

FIG. 4 is a rear view thereof.

FIG. 5 is a left view thereof.

FIG. 6 is a right view thereof; and,

FIG. 7 is a perspective view thereof.
